(57) **CLAIM**

The ornamental design for a 3-prong compression connector, as shown and described.

DESCRIPTION

FIG. 1 is a perspective view of the 3-prong compression connector of the present invention in a closed position;
FIG. 2 is a perspective view of the 3-prong compression connector of the present invention in an opened position;
FIG. 3 is a left side elevation view thereof in a closed position;
FIG. 4 is a right side elevation view thereof in a closed position;

FIG. 5 is a bottom plan view thereof;

FIG. 6 is a top plan view thereof;

FIG. 7 is a rear elevation view thereof in a closed position; and,

FIG. 8 is a front elevation view thereof in a closed position. The broken lines are shown in the views show unclaimed subject matter only and form no part of the claimed design.
